A. RUSH.

AUTOMATICALLY CLOSING FIRE SHUTTER.
APPLICATION FILED FEB. 28, 1907.

910,234.

Patented Jan. 19, 1909.

UNITED STATES PATENT OFFICE.

ALBERT RUSH, OF COLUMBUS, OHIO, ASSIGNOR TO THE KINNEAR MANUFACTURING COMPANY, OF COLUMBUS, OHIO, A CORPORATION OF WEST VIRGINIA.

AUTOMATICALLY-CLOSING FIRE-SHUTTER.

No. 910,234.

Specification of Letters Patent.

Patented Jan. 19, 1909.

Application filed February 28, 1907. Serial No. 359,719.

To all whom it may concern:

Be it known that I, ALBERT RUSH, a citizen of the United States, residing at Columbus, in the county of Franklin and State of Ohio, have invented a certain new and useful Improvement in Automatically-Closing Fire-Shutters, of which the following is a specification.

The invention relates more particularly to that class of fire resisting shutter or curtain which is normally held in raised position and is automatically released to close the opening for which it is designed upon the occurrence of fire.

Rolling fire resisting shutters or curtains, as now commonly constructed, are of iron and are heavy, and hence when automatically released to close the opening are likely to descend with great violence. Further, after they have descended they may be difficult to push up by hand, thus making ready escape from or access to the building difficult and sometimes impracticable.

The object of this invention, therefore, is the provision of means whereby, after the curtain has been released and partially unrolled, a counterbalancing effect shall be applied or added for the purpose of resisting or opposing violence in its descent, and for permitting the curtain to be easily raised or at least partially raised and sufficiently for the purpose of permitting ingress to or egress from the building.

The invention resides in the construction and combination of parts hereinafter described and pointed out in the claims.

In the accompanying drawings, forming part hereof and illustrating but one embodiment of the invention—Figure 1 is a front exterior elevation showing the roller, a fraction of the curtain, and other parts in section, the position of the parts being substantially that when the curtain is wound up or raised; Fig. 2 is a side elevation of the right hand end bracket and the parts attached thereto, as shown in Fig. 1; Fig. 3 is a view of the top of what is shown in Fig. 2; Fig. 4 is a horizontal sectional view on the line $x-x$ Fig. 1, but on a magnified scale, a portion of the roller being broken out.

In the views 1 and 1^a designate the usual end brackets for supporting the roller.

2 is a stud shaft pinned as at 2^a to the

left hand end of the roller and journaled in 55 the left hand end bracket 1^a.

3 designates the drum or sheet metal cylinder of the roller within which are secured collars 4 and 4^a perforated centrally to turn on a shaft 5 in the right hand 60 end of the roller.

Secured to the collar 4 and to a suitable small collar 5^a pinned to the shaft is a coiled spring 6 so that if said shaft be held and the drum turned the spring will be put 65 under tension. The shaft 5 projects through and is journaled in a bearing in the right hand end bracket 1.

Secured on the shaft 5 beyond the right hand end bracket is a wheel 7 having teeth 70 7^a one of which, when the curtain is turned up to the desired extent, is engaged by a lever 8 pivoted at 8^a on the outer side of the bracket 1, said lever being provided with a suitable lug or lugs 8^b to engage the tooth 75 7^a, or so as to prevent the unrolling of the curtain. To hold the lever 8 engaged with the wheel 7, a latch 9 pivoted at 9^a to ears on the bracket is provided, said latch being held in lever-engaging position by means of 80 a wire 10 stretched between a fixed point 10^a and the latch. The wire 10 is made up of sections united by a material 11—solder for example—fusible or disintegrable by a dangerous rise of temperature due to proximate fire. Upon such rise of temperature, therefore, the solder will soften and release the sections of wire 10, the latch 9, and lever 8, which falling out of the way release the wheel 7 and permit the curtain to unwind and descend. In the present instance the weight of the unrolled portion of the curtain is indicated to be such as to cause the curtain to descend, but devices can be provided to give the curtain vertical 95 movement downward if desired or necessary. In the present instance the wheel 7 is shown to have a hub projecting beyond the face of the wheel, as indicated at 7^b.

12 designates a metallic bar mounted to 100 slide laterally on pins 13 and 13^a secured to the outer side of the end bracket 1. This bar is tapped at its middle with a threaded hole and the threads of the tap are engaged by the threaded end 5^b of the shaft 5 so that 105 when the shaft is turned in the curtain-unwinding direction the bar is moved laterally toward the hub of the wheel 7. The bar 12

is normally so located with reference to the end of the hub that a given number of turns of the shaft will fetch the bar against the hub and thus made to serve as a brake to check or 5 stop the rotation of the shaft. The number of turns of the shaft is to be determined in each instance by the length of the curtain and by the strength of the spring, it being the desideratum that the shaft cease its rotation and that the curtain begin to exert its weight and momentum on the spring at that point where, by the time the opening is closed, the curtain will be nearly or quite counterbalanced. Upon the release of the 10 wheel 7, therefore, the rotation of the shaft due to the descending curtain draws the brake-bar 12 toward and tightly against the hub with a clutch-like action. The pins 13, 13^a, as before indicated, prevent the turning 15 of the brake-bar and the shaft 5 is checked or held stationary. Under this condition the curtain exerts its momentum and weight on the spring, winding the spring tighter and tighter, until its tension quite or nearly 20 counterbalances the weight of the curtain and so prevents its further descent. The arrangement, of course, can be such that the weight of the curtain is not completely counterbalanced when the curtain is completely 25 closed, but in either case the violence of the descent is relieved and in a graduated manner.

What I claim and desire to secure by Letters Patent is:

35 1. The combination with a curtain roller and curtain thereon, of a counterbalancing means to operate in connection therewith, and automatically operative means whereby after the curtain is partially unrolled, the 40 counterbalancing means is brought into operation to retard the further descent of the curtain.

2. The combination with a curtain roller and curtain thereon, of a counterbalancing 45 means to operate in connection therewith, and automatically operative means whereby after the curtain is partially unrolled the counterbalancing means is brought into operation to retard the further descent of the curtain, said means for bringing the counterbalancing means into operation also acting to release the counterbalancing means when the curtain is rolled up.

55 3. The combination with a curtain roller and curtain thereon, of a counterbalancing means to operate in connection therewith, a brake and automatically operative means in connection with said brake and the curtain and roller whereby after the curtain is partially 60 unrolled operative connection between the counterbalancing means and the curtain is effected and after the curtain is partially rolled up said connection is released.

4. The combination with a curtain and 65 roller therefor, of a shaft adapted to rotate

with the roller and with reference to which the roller can turn, a spring connected with the shaft, and means whereby said spring is rendered operative to counterbalance the curtain in a portion only of its descent.

5. The combination with a rolling curtain, of means whereby the same is held raised, said curtain adapted automatically to descend on the release of said means, a counterbalancing means to operate in connection with 75 the curtain, and automatically operative means whereby after the curtain is partially unrolled the counterbalancing means is brought into operation to retard the further descent of the curtain.

6. The combination with a curtain and roller therefor, of a shaft adapted to rotate with the roller and with reference to which the roller can turn, a counterbalancing device controlled by the shaft, a releasable 85 latch for holding the shaft from rotation in the raised position of the curtain, and means for checking the rotation of the shaft after the curtain is partially unwound whereby the counterbalancing means is made effective 90 on the curtain during a portion only of its descent.

7. The combination with a curtain and roller therefor, of a shaft adapted to rotate with the roller and with reference to which the roller can turn, a counterbalancing device controlled by the shaft, a releasable latch for holding the shaft from rotation in the raised position of the curtain, and means for automatically checking the rotation of 95 the shaft after the curtain is partially unwound whereby the counterbalancing means is made effective on the curtain during a portion only of its descent.

8. The combination with a curtain and 100 roller therefor, of a shaft adapted to rotate with the roller and with reference to which the roller can turn, a spring connecting the shaft and roller, means for latching the shaft from rotation in the raised position of 110 the curtain, means for releasing said latching means, a brake for the shaft, and means whereby the brake is operated to lock the shaft after the curtain is partially unwound 115 whereby tension is produced in the spring during a portion only of the descent of the curtain.

9. The combination with a curtain and roller therefor, of a shaft adapted to rotate with the roller and with reference to which 120 the roller can turn, a spring connecting the shaft and roller, means for latching the shaft from rotation in the raised position of the curtain, means for releasing said latching means, a brake for the shaft, said brake being operated by the shaft to lock the same from rotation after the curtain is partially unwound whereby tension is produced in the spring during a portion only of the descent 125 of the curtain.

10. The combination with a curtain and roller therefor, of a shaft adapted to rotate with the roller and with reference to which the roller can turn, a spring connecting the shaft and roller, means for latching the shaft from rotation in the raised position of the curtain, means for automatically releasing said latching means, a brake for the shaft, and means whereby the brake is automatically operated to lock the shaft after the curtain is partially unwound whereby tension is produced in the spring during a portion only of the descent of the curtain.
11. The combination with a curtain and roller therefor, of a shaft adapted to rotate with the roller and with reference to which the roller can turn, a spring connecting the shaft and roller, means for latching the shaft from rotation in the raised position of the curtain, means for releasing said latching means, a brake having threaded connection with the shaft whereby the brake is operated
- 5 to lock the shaft after the curtain is partially unwound and tension is produced in the spring during a portion only of the descent of the curtain.
- 10 15 20
12. The combination with a curtain and roller therefor, of a shaft adapted to rotate with the roller and with reference to which the roller can turn, a spring connecting the shaft and roller, means for latching the shaft from rotation in the raised position of the curtain, means for releasing said latching means, a non-rotative brake having threaded connection with the shaft whereby said brake is moved against a part on the shaft to generate braking friction after the curtain is partially unwound and tension is produced in the spring during a portion only of the descent of the curtain.
